CLAIM

The ornamental design for a side ledge with side stick, as shown and described.

DESCRIPTION

FIG. 1 is a forward view into an aircraft cockpit with seats removed showing our new design of a side ledge with side stick;

FIG. 2 is a forward view into an aircraft cockpit with seats included showing the side ledge with side stick of FIG. 1; FIG. 3 is a perspective view of the side ledge with side stick of FIG. 1 on the right side of the aircraft cockpit;

FIG. 4 is a perspective view of the side ledge with side stick of FIG. 1 on the left side of the aircraft cockpit;

FIG. 5 is a side view of the side ledge with side stick of FIG. 1 on the left side of the aircraft cockpit;

FIG. 6 is a side view of the side ledge with side stick of FIG. 1 on the right side of the aircraft cockpit;

FIG. 7 is a top view of the side ledge with side stick of FIG. 1 on the left side of the aircraft cockpit; and,

FIG. 8 is a top view of the side ledge with side stick of FIG. 1 on the right side of the aircraft cockpit.

In FIGS. 1-8, broken lines indicate environmental structure that forms no part of the claimed design.
